(57) **CLAIM**

The ornamental design for a bike light with portable power bank, as shown and described.

DESCRIPTION

FIG. 1 is a perspective view of a bike light with portable power bank showing our new design;

FIG. 2 is a perspective rear view thereof;

FIG. 3 is a perspective bottom view thereof;

FIG. 4 is a perspective bottom rear view thereof;

FIG. 5 is a front view thereof;

FIG. 6 is a rear view thereof;

FIG. 7 is a top view thereof;

FIG. 8 is a bottom view thereof;

FIG. 9 is a right side view thereof;

FIG. 10 is a left side view thereof;

FIG. 11 is a left side view thereof, having the sidebar cover in open position showing micro USB (Universal Serial Bus) and USB outlets of the power bank;

FIG. 12 is a perspective view thereof having the sidebar cover in open position; and,

FIG. 13 is a perspective view thereof, having the base rotated showing different angles on the handlebar.

The broken lines representing portions of the instrument are included for environmental purposes only and form no part of the claimed design.
